(57) **CLAIM**

The ornamental design for an electronic light bulb with a matrix flame, as shown and described.

DESCRIPTION

FIG. 1 is a front view of the electronic light bulb of the present disclosure;

FIG. 2 is a rear view of the electronic light bulb of FIG. 1; FIG. 3 is a right side view of the electronic light bulb of FIG. 1;

FIG. 4 is a left side view of the electronic light bulb of FIG. 1; FIG. 5 is top view of the electronic light bulb of FIG. 1; FIG. 6 is a bottom view of the electronic light bulb of FIG. 1; FIG. 7 is a perspective view of the top of the electronic light bulb of FIG. 1;

FIG. 8 is a perspective view of the bottom of the electronic light bulb of FIG. 1;

FIG. 9 is a front elevational view of a second embodiment of an electronic light bulb with a matrix flame showing my new design thereof;

FIG. 10 is a rear view of the electronic light bulb of FIG. 9; FIG. 11 is a right side view of the electronic light bulb of FIG. 9;

FIG. 12 is a left side view of the electronic light bulb of FIG. 9;

FIG. 13 is a top view of the electronic light bulb of FIG. 9; FIG. 14 is a bottom view of the electronic light bulb of FIG. 9;

FIG. 15 is a perspective view of the top of the electronic light bulb of FIG. 9; and,

FIG. 16 is a perspective view of the bottom of the electronic light bulb of FIG. 9.

The broken lines of FIGS. 1-16 are provided for purposes of illustration and form no part of the claimed design of the present application. However, the broken lines are intended to provide explicit disclosure as to presently unclaimed portions of the design, and Applicant reserves the right to pursue and claim such other presently unclaimed portions in one or more continuation applications.
